UNITED STATES PATENT OFFICE.

GEORGE J. HAFNER, OF ROCHESTER, NEW YORK, ASSIGNOR TO UNITED PRINTING MACHINERY COMPANY, OF JAMAICA PLAIN, MASSACHUSETTS, A CORPORATION OF MASSACHUSETTS.

BRONZING-MACHINE.

1,135,788.

Specification of Letters Patent. Patented Apr. 13, 1915.

Application filed June 17, 1912. Serial No. 704,093.

To all whom it may concern:

Be it known that I, GEORGE J. HAFNER, of Rochester, in the county of Monroe and State of New York, have invented certain new and useful Improvements in Bronzing-Machines; and I hereby declare that the following is a full, clear, and exact description thereof, reference being had to the accompanying drawings, which form part of this 10 specification.

This invention is a novel improvement in so-called "bronzing" machines by which fine metallic powders are applied to paper or fabric; and the present invention is an 15 improvement upon that type of machine wherein the bronzing is effected by means of a cylinder and co-acting rolls and pads which thoroughly rub the bronze powders into the sizing on the paper or fabric—such 20 operations being performed in a chamber through which the paper is passed and into which the bronzing powders are introduced and any surplus bronze powder introduced into the chamber is brushed from the paper 25 or fabric and withdrawn from the chamber by means of a suction fan or pump; and the powder laden air is usually discharged from said chamber into a separator preferably of the so-called "cyclone" type, by which the 30 powder is separated from the air, while the purified air escapes into the atmosphere.

The present invention in particular is an improvement upon the type of machine shown in Patent No. 797,080 to M. Smith, 35 dated August 15, 1905, wherein the parts are so arranged that the separated bronzing powders are returned to the bronzing chamber; the bronze laden air passing from the bronzing chamber to the fan chamber and 40 thence to the separator, and sufficient suction being maintained in the bronzing chamber to induce a flow of air thereinto through any openings or crevices; thus preventing the bronzing powders escaping from the chamber 45 into the operating room, or outside of the machine; the presence of such powders in the operating room being objectionable and detrimental to health. I have discovered in the operation of machines of this 50 type that some of the surplus bronzing powder withdrawn from the bronzing chamber has been moistened by the size on the paper or fabric being treated, and such 55 damp or moistened powder is liable to agglomerate and if immediately returned to

the bronzing chamber will affect the quality of the work.

The object of my invention is to separate such moistened or sized particles of powder from the dry powder, and to collect such 60 moistened particles in a suitable receptacle so that they may be thoroughly dried before being returned to the bronzing chamber. In this way I obtain improved results in the 65 operation of the machine and in the quality of work produced thereby.

I will now explain the invention more in detail with reference to the accompanying drawings in which I have conventionally illustrated a bronzing machine to which my 70 invention is applied.

In the claims annexed to the description I have summarized the features of the invention for which protection is desired.

In said drawings—Figure 1 is a diagrammatic side elevation partly in section of a complete bronzing apparatus embodying my invention. Fig. 2 is a transverse sectional view of such machine.

As stated the bronzing machine itself may 80 be of any desired type. As indicated in the drawings, the said machine preferably comprises a casing 1 within which is a bronzing cylinder 2 which is rotatably mounted within a substantially closed bronzing chamber 85 1^a in said casing. The cylinder 2 is provided with grippers 2^a, or other suitable devices, adapted to take sheets from a feed table 1^b and carry them past the bronzing devices and eventually surrender them to a 90 delivery cylinder 3.

The bronzing devices co-acting with the cylinder comprise a fountain or hopper 2^c from which the bronzing powder is fed by a suitable regulating device, onto the paper or fabric on cylinder 2, and after passing the hopper the powder is rubbed into the sized portions of the sheet by means of buffering rolls 2^b and vibrating pads 2^d; then the sheet is carried past buffering rolls 2^e which clean 100 and finish the sheet; and the bronzed sheet is taken from cylinder 2 by cylinder 3 and delivered thereby to a fly 3^a which lays the sheets upon a suitable receiver.

The chamber 1^a communicates at bottom 105 with an air trunk 4; and a screen 1^c may be placed in the bottom of the chamber 1^a to prevent paper or rough material mixing with the surplus bronze powder deposited therein.

The air trunk 4 communicates with a pump, or fan chamber, 4^a, in which is a, preferably, centrifugal fan or blower by which air is sucked into and through the chamber 1^a.

From the fan chamber 4^a the bronze laden air is conducted through a pipe 4^b to a cyclone separator 5 in which the bronze is separated from the air in the well known manner, the purified air escaping through an opening 5^a in the top of the separator into a hood 5^b from which the air may be conducted through a pipe 5^c out of doors, or to any other suitable point of discharge.

15 The powder precipitated in the separator 5 drops into a receptacle which may be in the form of a metal cylinder 6 having a conical top 6^a which is connected by a neck 6^c to the bottom of the separator 5 and by 20 which the separator may be supported; and the separator may be steadied by means of brace rods 6^d. This receptacle 6 may be supported on a shelf 1ⁿ attached to the casing 1, or to any other suitable support. The receptacle 6 has a door 6^e which may be closed in any suitable manner, preferably air tightly, and through which a vessel 7 may be introduced into the chamber to receive the heavy bronze powder dropped thereinto 25 from the separator 5. To insure that the air pressure in the receptacle 6 shall be less than the pressure in the lower part of the 30

separator 5 the upper part of the receptacle 6 is connected by means of a pipe 8 with the fountain or hopper 2^t; this pipe 8 may be conveniently connected to the conical top 6^a of receptacle 6 and to the top of the hopper 2^t as shown in the drawings. Air will be drawn from chamber 6 through pipe 8 into the hopper 2^t and thence through the air tubes 2ⁿ into the bronzing chamber 1^a as indicated in the drawings; this current of air being produced by the suction in chamber 1^a caused by fan 4^a.

45 A valve 6^v may be placed in the connection 6^c between the separator and the receptacle or depositing chamber 6 so that before the chamber is opened for the removal of the vessel 7 said valve may be closed to prevent the escape of dust laden air into the room, without necessitating the stoppage of the bronzing operations.

55 Operation: In the operation of the machine the fan maintains a partial vacuum in the bronzing chamber 1^a by withdrawing air therefrom and any loose or surplus powder admitted into the chamber, and brushed off of the paper or fabric being bronzed will be withdrawn from the chamber 1^a and discharged through pipe 4^b into the separator 5, wherein the particles of powder both moistened and dry will be deposited while the clear air escapes to the outlet pipe 5^c.
60 The separated bronze powder will descend by gravity into the receptacle or depositing
65

chamber 6 and the wet or moist particles of bronze powder will drop at once into the vessel 7, but the very light dry particles of powder floating in the upper part of the chamber 6 will be drawn into pipe 8 and returned to the fountain 2¹ wherein they are deposited by gravity. 70

The pipe 8 also serves to keep the air pressure in the depositing chamber 6 below the pressure in the cyclone separator, and this facilitates separation of the powders from the air in the separator. By this invention only perfectly dry bronze powder will be used in the machine, and therefore a much better quality of work is produced than in machines wherein the damp or moist powders are immediately returned to the bronzing chamber; because such damp powders have a tendency to adhere to the paper or fabric and produce mottled or speckled work; the wet powders also tend to agglomerate with particles of the dry powder and would eventually make the powder too thick and heavy for fine work. The moist or wet powder caught in the depositing chamber 6 can be removed when desired, and can be dried out before being returned to the fountain. By reason of the suction in the bronzing chamber and in the upper part of the depositing chamber 6 the bronze powder is prevented from escaping into the room.

What I claim is:

1. In combination, a bronzing machine having a bronze hopper, a bronzing chamber and bronzing devices therein; means for withdrawing bronze laden air from said chamber; and a cyclone separator into which the bronze laden air is discharged and the bronze separated from the air; with a depositing chamber into which the powders precipitated in the separator are discharged, and a return pipe connecting said chamber with the bronzing hopper, substantially as described. 100 105 110

2. In combination, a bronzing machine having a bronze hopper, a bronzing chamber, and bronzing devices in said chamber; means adapted to withdraw bronze laden air from said chamber; and a cyclone separator into which the bronze laden air is discharged and separated from the bronze; with a depositing chamber into which the precipitated bronze is discharged from said separator; and a suction pipe leading from said depositing chamber to the bronzing hopper; whereby while wet particles of powder are trapped in said depositing chamber the light dry particles may be returned to the bronzing hopper.

128
3. In a bronzing machine, the combination of a chamber communicating with the atmosphere; means for applying bronze to sheets of paper passing through said chamber; a fountain for supplying bronze to said 130

chamber; a suction fan or pump for withdrawing the bronze laden air from said chamber; and a separator into which said air is discharged; with a depositing chamber into which bronze precipitated in the separator is discharged, and a suction pipe communicating with the upper part of said depositing chamber and with the bronzing chamber whereby a partial vacuum is maintained in said depositing chamber and dry

particles of bronze powder may be returned therefrom to the bronzing chamber.

In testimony that I claim the foregoing as my own I affix my signature in presence of two witnesses.

GEORGE J. HAFNER.
